[57] CLAIM

The ornamental design for a safety razor with disposable blade, as shown and described.

DESCRIPTION

FIG. 1 is a front, top and side perspective view of the safety razor with disposable blade showing my new design;

FIG. 2 is a front end elevational view thereof;

FIG. 3 is a rear end elevational view thereof;

FIG. 4 is a side elevational view thereof, the side opposite being a mirror image of the side shown in FIG. 4.

FIG. 5 is a top plan view thereof;

FIG. 6 is a bottom plan view thereof;

FIG. 7 is a cross sectional view taken along line 7—7 of FIG. 4; and,

FIG. 8 is a cross sectional view taken along line 8—8 of FIG. 4.

FIG. 1

FIG. 2

FIG. 3

FIG. 4

FIG. 5

FIG. 6

FIG. 7

FIG. 8
